Des. 1471

John Gorham, Gorham Thurber & Lewis Decker of Providence, R. I.
Whole No. 1471 Letters Patent No. 106, dated Sept. 3, 1861.

The schedule referred to in these Letters Patent and making part of the same.

To all whom it may concern:

Be it known that we John Gorham, Gorham Thurber, and Lewis Decker Jr. of Providence, in the State of Rhode Island, have invented a new and original design for Table and other Spoons, and we do hereby declare that the following is a full, clear and exact description thereof, reference being had to the accompanying drawings making part of this specification, in which-

Fig. 1, is a plan of the upper, and

Fig. 2, of the under surface.

Fig. 3, a cross section of the widest part of the handle.

Fig. 4, a cross section of the stem of the handle.

Fig. 5 & 6, cross sections of the bowl, and

Fig. 7, a longitudinal section of the entire spoon.

In the accompanying drawings 2, represents the bowl of

Des. 1471

the spoon which instead of being egg shaped, with the widest and deepest end towards the handle, is of an entirely shape, as represented, the narrowest end being towards the handle, and the widest and deepest part about, or a little forward of, the middle of the length, and with the edges b., turned over on each side from a little back of the front end to the junction with the handle.

The stem c. of the handle is round or nearly so, gradually and slightly flattened and spread out at each end. And the rear end, at d., spreads out in an elliptic shape ornamented on the upper surface with leaves, spreading out on each side as at ff. and stems g, g. shooting out and curling over on each side of a central pointed piece, and beyond this other ornaments extend to the extremity of the rear end, and spreading out from the centre to each edge in curved lines as at h, h. And on the under surface there are spreading leaves ff. as on the upper surface, and beyond this an elliptic formed moulding i, i. surrounding a smooth surface, the said moulding being surrounded by a wreath of leaves j. and a double rosette, or equivalent finish at the tip end.

What we claim as new, and desire to secure by Letters Patent, is the design for Spoons, substantially as described.
